UNITED STATES PATENT OFFICE.

CHARLES G. GROTNES, OF CHICAGO, ILLINOIS.

FORMING MACHINE.

1,407,148.

Specification of Letters Patent. Patented Feb. 21, 1922.

Application filed September 30, 1919. Serial No. 327,550.

To all whom it may concern:

Be it known that I, CHARLES G. GROTNES, a citizen of the United States, residing at Chicago, in the county of Cook and State of Illinois, have invented certain new and useful Improvements in Forming Machines, of which the following is a specification.

My invention relates to machines for forming circular parts such as the rims of vehicle wheels by compressing a circular hoop to exact size and diameter with or without simultaneously shaping the edges or other portions thereof by means of suitable dies.

An object of my invention is to secure a high degree of uniformity in the finished product and to provide a machine which can be adjusted to secure not only uniformity but accuracy in the size of the rims produced.

Another object is to provide a machine which will handle the rims in such a position that they can be put in the machine and removed therefrom with great speed and very little effort by the operator.

Another object is to provide a machine of this type which will be much more reliable than those hitherto employed both as to durability in the wear and tear of service, and as to freedom from accidental breakage.

Further objects and advantages of my invention will become apparent as the description proceeds.

In the accompanying drawings, Figure 1 is a central longitudinal section of a machine embodying the principles of my invention. Fig. 2 is a transverse section through the connecting pin. Fig. 3 is an end view looking at the face of the machine along its axis, with portions broken away and in section. Fig. 4 is a detail view of the plunger, and Fig. 5 is a view of the cross head.

The herein described embodiment of my invention comprises a movable head carrying a plurality of segmental blocks radially slidable thereon, toggle mechanism for forcing the blocks inwardly, means for quickly and accurately adjusting the action of the toggle mechanism, a resilient connection for transmitting power during the return stroke of the head, and a framework carrying various parts of the machine and supporting them in an inclined position.

In the embodiment of my invention se-

lected for illustration, 10 designates a longitudinally extending frame supported in an inclined position on a foot 11 formed at the rear end thereof and a main supporting block 12 as clearly illustrated in Fig. 1. This frame has opposite walls 13 which I have illustrated in Fig. 2 as approximately channel-shape with the flanges turned outwardly. A pair of brackets 14 suitably bolted as at 15 to the upper and lower sides of the front end of the frame support a stationary ring 16 on four radially extending arms 17.

A circular plate or head 18 is mounted to reciprocate from a position removed rearwardly somewhat from that shown in Fig. 1 into the position illustrated in Fig. 1 and back again. The head 18 carries a plurality of segmental blocks 19 each block comprising a radial portion 20 radially slidable in a slot 21 in the head, and an axially extending portion 22. The axially extending portions define a hollow cup-shaped cavity within which the object to be compressed is to be placed.

A ring 23 overlying the front ends of the axially extending portions 22 of the blocks 19 and fastened to the head 18 by suitable bolts 24 confines all the blocks 19 slidably between itself and the face of the head 18. Each block 19 is moved axially toward and away from the center of the head as the head reciprocates, by a toggle mechanism comprising a pin 25 fastened through the axially extending portion 22 of the block, a similar pin 26 mounted in a stationary block 27 suitably attached to the stationary ring 16 and a link connection between said pins. The concavities in which the pins 25 and 26 rest are sufficiently deep to produce projecting portions or ears 25^a which serve to prevent displacement of the pins. The link connection between said pins comprises two tension links 28 engaging the projecting ends of the pins 25 and 26 and a compression link 29 having cylindrical sockets at its ends as clearly illustrated in Fig. 1 engaging the central portions of the pins 25 and 26. The force which may safely be exerted by a compression link such as 29 on the pins is obviously much greater than the shear strength of the pins.

While it is obvious that links 28 can trans-

mit compression as well as tension stresses, the length of the link 29 is considerably shorter and its cross section appreciably greater than the combined cross section of 5 links 28 so that the deformations under stresses will be such that most of the compression load will be carried by link 29.

Means for reciprocating the head 18 are provided comprising a plunger 30 suitably 10 engaging said head as by means of a central boss 31 and a circular flange 32 reinforced by ribs 33, on which boss and flange the head 18 fits and to which it is suitably attached. The plunger 30 as illustrated in Fig. 2 slides 15 between the walls 13 of the frame 10. Inwardly projecting flanges 34 suitably reinforced by webs 35 support the plunger 30 which moves in sliding contact with their upper face, a portion of the inner faces 20 of the opposing channels 13 and the lower face of a suitable retaining bracket 36. As illustrated the bracket 36 has side members of angle cross section suitably bolted as at 37 to the walls 13, and a pair of integral 25 cross pieces 38 and 39.

A cross head 40 of the shape indicated in Fig. 5 carries the pin 41 for the connecting link 42 actuated by the eccentric 43 to reciprocate plunger 30. This cross head 40 is of approximately U-shape, the bight being channel shape with an inclined web as indicated at 44 in Fig. 1 and the arms being 30 slide on inwardly projecting flanges 45 (see Fig. 2) on the plunger 30 engaging 35 suitable grooves in said cross head.

The plunger has a central cross-piece 46 which receives the thrust of the cross head 40 during the operating stroke through a spacing wedge 47 of rather acute taper. A 40 tension rod 48 projects from the bight of the cross head 40 through a suitable slot in the wedge 47 and a suitable hole in the cross piece a suitable distance beyond said cross piece to carry a nut 49 between which and 45 the cross piece the compression spring 50 is confined. On the return stroke the weight of the head and plunger might in most instances be sufficient to carry them back as the cross head moves back but in machinery of this sort accidents of a serious 50 nature are apt to occur by reason of tools or other objects accidentally being placed where they will fall into the machine and obstruct the rearward movement of the 55 head or plunger. Such an accident would ordinarily break the machine itself necessitating expensive repairs and delay. The resilient connection afforded by the spring 50 on the return stroke will allow the power 60 applied to the eccentric 43 to draw the cross head 40 back to its initial position without any more disastrous result than compressing spring 50.

A high degree of accuracy in the diameter 65 of the finished product is essential. I have

provided means for adjusting the final point to which the plunger and head will be carried by the compression stroke thus making possible a very precise adjustment of the diameter of the finished work. The wedge 70 47 is held in position by a spacing rod 51 suitably socketed at 52 at its lower end on the upper edges of the cross piece 46 and having engagement with the forwardly extending portion 53 at the upper end of the 75 wedge 47. The shaft 51 may be rotated by means of a suitable hand wheel 54 to shift the wedge 47 and adjust the stroke of the plunger and head.

Any suitable or preferred source of power 80 may be used to drive the eccentric 43. I have illustrated bearings conveniently formed in and mounted upon the frame 10 adapted to support a high speed shaft 55 which may be suitably geared to an intermediate shaft 56 which in turn may be 85 geared to the eccentric 43.

The inclined position in which my entire device stands upon the supporting floor or other structure is decidedly advantageous 90 in handling the work as the rims may be stacked on one side of the machine and rolled in front of and placed in the machine with a minimum expenditure of time and effort on the part of the workman, and similarly lifted out of the machine, dropped on edge on the floor and rolled away.

While I have illustrated and described in detail the embodiment of my invention at present preferred it should be clearly understood that the disclosure is for purposes of illustration only and that many variations and modifications will naturally occur to those skilled in the art. I aim in the subjoined claims to cover all such legitimate 100 modifications and variations.

I claim as my invention:

1. A device of the class described having, in combination, a plurality of radially 110 slideable and axially movable compression jaws, toggle means for moving said jaws radially upon axial movement thereof, and means for adjusting the axial movement of said jaws to vary the radial movement produced by said toggles. 115

2. A device of the class described having, in combination, a reciprocating head, radially slideable blocks on said head, toggle mechanism actuating said blocks in a radial direction upon axial movement of said head, 120 power means for moving said head axially and an adjustable connection for varying the stroke of said power means.

3. A device of the class described, having, in combination, stationary and movable parts, a power driven element adapted to reciprocate said moving parts and means providing a positive connection between said power driven element and said movable parts for motion in a direction to operate 125 130

upon the work and a resilient connection between said power driven element and said movable parts for motion in the other direction.

5 4. A device of the class described having, in combination, a plurality of radially slidable compression blocks defining a circular cavity, and means for moving said blocks radially, said blocks being located 10 in a plane inclined to the vertical.

5. A device of the class described having, in combination, a frame, a stationary ring supported by said frame, a reciprocating head adapted to move toward and away 15 from the plane of said ring, an annular series of radially slidable blocks carried by said reciprocating head and defining a circular space to receive material to be compressed, said head being at the side of said 20 space opposite to the open or receiving side, and toggle links connecting said radially slidable blocks with said stationary ring.

6. A device of the class described having, in combination, a plurality of radially 25 slidable jaws, means for imparting simultaneous axial movement to all of said jaws, means for moving said jaws radially upon axial movement thereof, and means for adjusting the axial movement of said jaws to 30 vary the radial movement produced thereby.

7. A device of the class described having, in combination, operating members defining a cavity, means for supporting said operating members with said cavity lying in a 35 plane inclined to the vertical, and means for actuating said members to operate upon a piece of material placed in said cavity.

8. A device of the class described having, in combination, a frame, a stationary ring 40 supported by said frame, a reciprocating head adapted to move toward and away from the plane of said ring, radially slidable blocks carried by said reciprocating head, toggle links connecting said radially slidable 45 blocks with said stationary ring, a reciprocating member, a positive connection between said reciprocating member and said head for moving said head toward the plane of said ring, and a resilient connection between said member and said head for moving said head in the opposite direction.

9. A device of the class described having, in combination, a frame, a stationary ring supported by said frame, a reciprocating 55 head adapted to move toward and away from the plane of said ring, radially slid- able blocks carried by said reciprocating head, toggle links connecting said radially slidable blocks with said stationary ring, a 60 reciprocating member, a positive connection between said reciprocating member and said head for moving said head toward the plane of said ring, a resilient connection between said member and said head for moving said head in the opposite direction, and quickly

adjustable means interpolated in said positive connection for adjusting the stroke of said head.

10. A device of the class described having, in combination, a frame, a stationary ring supported by said frame, a reciprocating head adapted to move toward and away from the plane of said ring, radially slid- able blocks carried by said reciprocating head, toggle links connecting said radially slidable blocks with said stationary ring, a slid- able plunger carrying said head, a cross head slidably mounted in said plunger, means for imparting a reciprocating motion to said cross head, a positive connection operating by abutment against one face of said cross head for forcing said plunger in one direction, and a resilient connection allowing relative sliding motion between said cross head and plunger adapted to resiliently urge said plunger in the opposite direction.

11. A device of the class described having, in combination, a frame, a stationary ring supported by said frame, a reciprocating head adapted to move toward and away from the plane of said ring, radially slid- able blocks carried by said reciprocating head, toggle links connecting said radially slidable blocks with said stationary ring, a slid- able plunger carrying said head, a cross head slidably mounted in said plunger, means for imparting a reciprocating motion to said cross head, a positive connection operating by abutment with one face of said cross head for forcing said head toward the plane of said ring, a wedge shaped member interpolated in said positive connection, and means for adjusting the position of said wedge shaped member to vary the stroke of said head.

12. A linkage for a toggle connection having, in combination, pins located in relatively movable members, a tension or compression link pivotally connected between the ends of said pins, and a link adapted to transmit compression only extending between said pins and having fitting faces at its ends abutting said pins.

13. A device of the class described having, in combination, a stationary ring, a head 115 movable toward and away from the plane of said ring, radially slidable members carried by said head and toggle links connecting said members to said ring, each link comprising circular pins mounted in said radially 120 slidable member and said stationary ring, a link pivotally engaging one end of each of said pins and adapted to transmit either tension or compression and a link adapted to transmit compression only extending from 125 one pin to another and having its ends fitting upon and abutting the surfaces of said pins.

14. A linkage for a toggle connection having, in combination, relatively movable mem- bers, pins passing through said members and 130

having contact therewith from side to side of said members over a considerable portion of the cylindrical surface of the pin, ears on said members overlying portions of 5 said pins to hold them in place, compression links abutting the portions of said pins not covered by said ears, said pins projecting

beyond the sides of said members and additional links connecting the projecting portions of said pins.

10

In testimony whereof, I have hereunto set my hand.

CHARLES G. GROTNES.
